UNITED STATES PATENT OFFICE.

RALPH A. FREUNDLICH, OF BROOKLYN, NEW YORK.

DOLL TOY.

Application filed May 16, 1925. Serial No. 30,654.

My invention relates to a toy in the form of a doll provided with a hollow head made of resilient material having represented thereon the usual doll features which may be applied by painting, spraying or other means, and the objects of this invention are to provide the doll with a soft and readily collapsible head and also to permit the doll to do certain tricks by permitting it to fall upon its head and utilizing the body and legs as a means of throwing the doll into different positions to cause the doll to turn in different directions, dependent upon which portion of its head is first allowed to contact with a solid surface.

In the drawings Fig. 1 represents a front view of the doll; Fig. 2 a section on the line 2—2 through the body of the doll and through a portion of the right leg thereof; Fig. 3 represents the underside of the doll head viewed from the portion thereof which rests on the body of the doll.

The head 1 of the doll comprises resilient rubber material and for this purpose rubber play balls may be used which are soft but, nevertheless, have the capacity of extending themselves after being compressed. The resilient head 1 is attached to the body 2 of the doll by forming a slit 3 in the underside 30 of the head and clamping it by the means shown in Fig. 2 to the fabric 4 which constitutes the outer casing of the body. The clamping means comprise the inner metal washer member 5, the integral sheet metal saucer shaped member 6, the end washer 7 and corresponding members 5^a, 6^a and 7^a which are inside of the doll body and underneath the fabric 4 at the portion constituting the neck of the doll. The parts 6 and 7 are apertured and by means of the apertures are threaded over an ordinary galvanized nail 8 and then forced through the slit 3 into the hollow body of the head. The end of the nail is then pushed through the fabric 4 constituting the casing for the body of the doll and the corresponding parts 5^a, 6^a and 7^a are threaded through apertures therein over the nail so that the washers 5 and 5^a lie respectively on the inner surface of the rubber ball head and on the inner surface of the fabric constituting the upper portion of the doll body. By means of pliers the end of the nail is then formed into a curl 8^a to cause the two washers 5 and 5^a to securely clamp the rubber ball and the fabric of the body to-

gether and to make such union comparatively airtight. It is to be understood that for this purpose the lower portion of the doll body at 4^b is left open and after these operations are completed the body of the doll is securely stuffed with cotton or other filler, the bottom thereof sewn closed and the legs 11 of the doll then sewn to the body to form a flexible joint 12. The head 1 of the doll is painted with the representations of eyes, nose, lips and hair as shown in Fig. 1. It is preferred to perforate the rubber head of the doll between the lips and to insert therein the end 9 of a rubber balloon 10. The rubber balloon may be inflated by squeezing the head of the doll, thereby forcing the air therefrom into the balloon. The balloon 10 is made removable so that it may be replaced at will with balloons of different colors.

The entire doll head and body being soft and compressible provides a safe toy for babies to play with, without fear of injury to themselves, as has not been the case with dolls having heads of wood pulp or other hard composition. In addition to these advantages the doll, by the utilization of a rubber ball as the head, may be caused to do different stunts by dropping it so that the head first strikes a hard surface. Each particular stunt will vary according to which portion of the doll head first strikes a hard surface and in this manner the doll can be caused to do a somersault, turn on its side, rise to a sitting position, utilizing the momentum thereby given to the body and legs of the doll as a means of throwing the entire doll to such different positions.

What I claim is:

A doll toy comprising a stuffed body, a head consisting of a thin walled hollow rubber ball, substantially smooth on the outside, doll features painted upon the front portion of the smooth outer surface, an aperture through the wall of the head in proximity to the painted mouth, a balloon having its end secured in the aperture and adapted by pressure on the head to be inflated and deflated by the removal of said pressure, said head being clamped to the body by a pin, one end of which is secured inside of the body and the other end inside of the head and legs on the body.

In testimony whereof I have hereunto set my hand.

RALPH A. FREUNDLICH.
